(57) **CLAIM**

The ornamental design for a golf putting mat as shown and described.

DESCRIPTION

FIG. 1 is a front, left, and top perspective view of a golf putting mat, showing my new design;

FIG. 2 is a rear, right, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is detailed view taken from encircled portion labeled "9" in FIG. 1; and,

FIG. 10 is detailed view taken from encircled portion labeled "10" in FIG. 2.

The short-dash and long-dash broken lines in FIGS. 1, 2, 9 and 10 denote the boundaries of the detail areas and form no part of the claimed design. The even broken lines in the drawings are portions of the golf putting mat and form no part of the claimed design.
